DESIGN FOR A BADGE

Henry J. Hanson, Chicago, Ill., assignor to City of Chicago, a municipal corporation

Application November 25, 1935, Serial No. 59,757

Term of patent 14 years

To all whom it may concern:

Be it known that I, Henry J. Hanson, a citizen of the United States, residing in Chicago, in the county of Cook and State of Illinois, have invented a new, original, and ornamental Design for a Badge, of which the following is a specification, reference being had to the accompanying drawing, forming part thereof:

In the drawing Figure 1 is a front view of a badge showing my new design.

I claim:

The ornamental design for a badge as shown.

HENRY J. HANSON.
